(57) **CLAIM**

The ornamental design of a top for a water filter cartridge, as shown and described.

DESCRIPTION

FIG. 1 is a perspective view of the top to a water filter cartridge of the present invention, said water filter cartridge being shown in broken lines to show the top's environment; FIG. 2 is a rotated perspective view of the top for a water filter cartridge;

FIG. 3 is a top plan view thereof;

FIG. 4 is a front elevational view thereof;

FIG. 5 is a left side elevational view thereof;

FIG. 6 is a rear elevational view thereof;

FIG. 7 is a right side elevational view; and,

FIG. 8 is a bottom plan view thereof.

The broken line showing of the filter cartridge is for the purpose of illustrating environmental structure and forms no part of the claimed design.
